Attest:

UNITED STATES PATENT OFFICE.

BENJAMIN F. HUBBELL, OF CAMBRIDGE, MASSACHUSETTS, ASSIGNOR TO CARR
FASTENER COMPANY, OF CAMBRIDGE, MASSACHUSETTS, A CORPORATION
OF MAINE.

FASTENER.

Application filed August 13, 1921. Serial No. 491,911.

To all whom it may concern:

Be it known that I, BENJAMIN F. HUBBELL, a citizen of the United States, and resident of Cambridge, in the county of Middlesex, State of Massachusetts, have invented an Improvement in Fasteners, of which the following description, in connection with the accompanying drawings, is a specification, like characters on the drawings 10 representing like parts.

This invention pertains to improvements in fasteners. It is among the objects of the invention to provide a fastener of superior construction and appearance, and preferably one which may, if desired, be locked against separation of the parts by lateral strain between stud and socket.

In the drawings, which show a preferred form of one embodiment of my invention:

20 Figure 1 is a front elevation of two pieces of fabric held together by a preferred form of fastener;

Fig. 2 is a section on the line 2—2 of Fig. 1, being partly in elevation;

25 Fig. 3 is a front elevation of a preferred form of socket illustrated in Fig. 1;

Fig. 4 is a rear elevation of the socket illustrated in Fig. 3;

30 Fig. 5 is a section on the line 5—5 of Fig. 4;

Fig. 6 is a plan view of a modified form of socket; and

35 Fig. 7 is a section on the line 7—7 of Fig. 6.

Referring to the drawings and to the preferred form of my invention selected for 40 illustrative purposes, I have shown a stud including a head 6, a neck 7 and a base 8 secured by stitching 9 to the stud-carrying fabric 10. The preferred form of socket illustrated includes a casing having a plate 11, preferably circular as illustrated, and centrally apertured at 12 for passage of the head of the stud therethrough. The casing

45 contains the resilient means for gripping the head of the stud typified by the spring 13, providing jaw portions 14 and 15 intersecting opposite sides of the aperture 12 in the socket casing. The socket casing may be

50 parallelly flanged at 20 to contain and overlie the spring 13 and may be secured to the socket carrying fabric 21 by the stitches 22. In the preferred form of my invention illustrated, the socket casing adjacent the stud-

55 receiving aperture 12 therein is provided

with a struck-up flange 16 which, as illustrated, is preferably somewhat larger than the stud-receiving aperture so as to provide a lip 17 around all or portions of the stud-receiving aperture which the head of the 60 stud may overlie when engaged in the socket. The preferred form of my invention illustrated includes at one side of the stud-receiving aperture and in this doubled portion of the socket casing a notch or lateral extension 65 18 corresponding to the notch illustrated in United States Letters Patent to Fred S. Carr No. 1,365,022, issued January 11, 1921. The purpose of this notch is to provide a lock between stud and socket when under lateral 70 strain in the direction of the notch, this lock, however, preferably being insufficient to permit separation of stud and socket even when under some lateral strain pursuant to relative tipping between stud and socket in a direction somewhat greater than the angle which is likely to be produced by the resolution of forces between stud and socket when under strain.

The struck-up flange or rim 16 serves the 80 function normally served by the dome of fasteners in that it is slotted to permit passage therethrough of the jaw portions 14 and 15 of the spring 13, the portions of the flange 16 overlying such slots serving to hold down 85 the jaw portions 14 and 15 of the spring against displacement when the head of the stud is entered in the socket, while permitting the spring jaws to yield as the stud is entered and to spring back into engagement with the 90 neck of the stud after the latter is entered in the socket. In the preferred form of my invention illustrated, the spring jaws 14 and 15 are not parallel but flare away from each other in the direction of the notch 18, thus 95 providing adjacent the notch 18 a flange of considerably greater strength than could be provided if the jaw portions were parallel. The flaring of the jaws 14 and 15 also serves 100 to press or urge the neck of the stud toward the notch 18 when entered between the jaws 14 and 15. The flange 16 preferably, as illustrated, terminates at or below the plane of the adjacent edge of the socket casing so that the flange does not thicken the socket as a whole, as is usually the case where a dome is used. The flange 16 being spaced away from the stud-receiving aperture, permits 105 the neck of the stud to engage over the adjacent edge of the socket without that result- 110

ant tipping between stud and socket which is normally present in stud and socket fasteners of the dome type. While the stud and socket illustrated are of the type adapted to be sewn to their carrying fabrics, my invention is also of use in fasteners of the types adapted to be otherwise secured to their carrying elements.

While I have shown and described a preferred form of one embodiment of my invention in Figs. 1 through 5, there are certain advantages appertaining to the modification of my invention illustrated in Figs. 6 and 7, wherein the struck-up flange or rim 16 is somewhat enlarged, preferably being made circular to provide a greater overhang over the jaw portions of the spring and to provide a double thickness of metal at the sides of the stud-receiving aperture as well as at the ends thereof.

It will be understood that changes involving omission, substitution, alteration and reversal of parts, and even changes in the mode of operation, may be made without departing from the scope of my invention, which is best defined in the following claims:

1. A fastener comprising, in combination, a stud having a head and a neck and a socket including a casing presenting a stud-receiving aperture, a reversely flanged portion of the casing at the edge of said aperture to present a double thickness of metal and a smooth edge, spring means intersecting said aperture to grip the neck of said stud when entered therein, an upstanding flange presenting a part overlying said spring means while permitting stud-engaging and disengaging movement thereof and a lateral extension of said aperture within said upstanding flange to provide a lock against undesired separation of stud and socket when under lateral strain.

2. A fastener comprising, in combination, a stud having a head and a neck and a socket including a casing providing a plate having a stud-receiving aperture therethrough, and a flange formed integral with said plate and surrounding in spaced relationship the stud-receiving aperture in said plate, said flange slotted to permit passage therethrough of resilient stud-engaging means.

3. A fastener comprising, in combination, a stud having a head and a neck, a socket

including a plate having a stud-receiving aperture therein and providing a reversely bent lip surrounding said aperture and an upstanding flange slotted to permit passage therethrough of a stud-engaging jaw and a notch through said plate and said lip communicating with said aperture.

4. A fastener comprising, in combination, a stud having a head and a neck and a socket including a casing having a stud-receiving aperture at one side thereof and a notch in said casing communicating with said aperture to provide a lateral extension thereof, and a spring in said casing, said spring providing two jaw portions intersecting opposite sides of said stud-receiving aperture and inclined away from each other in a direction toward said notch whereby the head of said stud when entered in said aperture may be urged toward said notch by said jaw portions.

5. A socket for stud and socket fasteners comprising a casing providing a stud-receiving aperture therein, a reversely bent lip adjacent said aperture and an upstanding flange surrounding said aperture in spaced relation thereto, a notch communicating with said aperture and forming a lateral extension thereof, a spring in said casing, slots through said upstanding flange to guide the stud-engaging portions of said spring intersecting said stud-receiving aperture, said slots positioned to spread the ends of said spring away from one another in the direction of said notch.

6. A socket for stud and socket fasteners comprising, in combination, a casing providing a plate having a peripheral flange and providing a stud-receiving aperture therein, said stud-receiving aperture notched or extended at one side, a spring in said casing, a flange surrounding the stud-receiving aperture in said casing and guiding the stud-engaging portions of said spring, and a notch communicating with said aperture, said flange terminating adjacent the plane of that side of the socket toward which said flange extends and providing an open side through which the head of the stud may pass when engaged with the socket.

In testimony whereof, I have signed my name to this specification.

BENJAMIN F. HUBBELL.
